UNITED STATES PATENT OFFICE.

HERMAN WALCH, OF MASON CITY, IOWA, ASSIGNEE OF ONE-HALF TO PATRICK J. DOUGHERTY, OF MASON CITY, IOWA.

AIR-BRAKE COUPLING.

1,012,770.

Specification of Letters Patent. Patented Dec. 26, 1911.

Application filed August 10, 1910. Serial No. 576,528.

To all whom it may concern:

Be it known that I, HERMAN WALCH, a citizen of the United States, residing at Mason City, in the county of Cerro Gordo and State of Iowa, have invented new and useful Improvements in Air-Brake Couplings, of which the following is a specification.

This invention relates to an improved air brake coupling and has for its principal object to equip an automatic car coupling of any preferred type with my improvement, whereby when the cars are coupled or uncoupled the air brake line will also be automatically coupled or uncoupled, and thus in this manner my invention will dispense with the services of the brakeman now commonly employed for coupling and uncoupling air brake lines.

Another object of the invention is to provide a coupling of the class described which is extremely simple in construction, positive in operation and cheap to install.

With these and other objects in view, the invention consists in the construction and novel combination of parts hereinafter more fully described, illustrated in the accompanying drawing, and pointed out in the claims hereto appended; it being understood that various changes in the form, proportion, size and minor details of construction within the scope of the claims, may be resorted to without departing from the spirit or sacrificing any of the advantages of the invention.

In the drawing, Figure 1 is a top plan view of a coupling showing my improved air brake coupling associated therewith, Fig. 2 is a side elevation of the same, Fig. 3 is a partial sectional view taken on the line 3-3 of Fig. 1, and Fig. 4 is a perspective view of one of the air valves.

Like reference numerals designate corresponding parts in all the figures of the drawing.

Referring to the drawing, the invention comprises coupling heads 5-5 of any preferred type, each head being provided with a knuckle extension 6, said extension being bifurcated to form a recess 7 and consequent ears 8-8. The invention further comprises knuckles 9-9 which are respectively associated with knuckle extensions 6-6. Each knuckle is provided with a leaf 10 adapted to be seated within the recess 7 and between

the ears 8-8 of the said extension. Packing rings 11-11 of any suitable material, are respectively arranged between the ears 8 and the leaf 10 for a purpose hereinafter described. A pivot pin 12, for the knuckles 9, is composed of a rounded shank 13, a squared head 14 and a projecting nipple 15. The shank of this pin passes through the ears 8 and the leaf 10 and the squared head 14 is seated within a correspondingly shaped recess 16, formed in one of the said ears 8, the nipple 15 thereby projecting beyond the said ear 8. It will be observed at this point that the pin is held in immovable position while the knuckle can be swung around thereon. Formed within the pin is a longitudinal channel 17 having one end communicating with the nipple 15 and the other end communicating centrally with the exterior of the pin.

Respectively formed in the body of the knuckles and contiguous to the opposed faces thereof, are dove-tailed recesses 18. Also formed in each of the said knuckles is a channel or air duct 19 which communicates with the said recess 18 and the channel 17 formed in the said pin. Seated within each of the said recesses 18 is a gasket member 20, preferably formed of rubber, although any other material may be employed if desired. This member comprises a body portion 21 of dove-tailed shape and adapted to be normally held within the said recess 18 by its peculiar shape, and an end flange 22 adapted to normally project beyond the outer face of the knuckle, said flange being provided centrally with a depression 23 and a longitudinal channel 24 which communicates with the said depression 23 and the channel 19.

Connected to the nipple 15 is an air pipe 25. Coil springs 26-26 are preferably mounted within each of the coupling heads 5 to bear against the knuckle 9 and thereby assist in holding the said flanges 22 of each gasket member 20 in tight relation.

From the foregoing, it will be seen that when the knuckles of the coupling are in the position shown in Fig. 1, air can pass from the pipe 25 through the channel 17 of the pin into the channel 19 formed in the knuckle and through the gasket member 20, and so on. When, however, it is desired to uncouple the car, the knuckles 9 will of course be swung about the pivots 12 and as

a result the channels 19 will be thrown out of register with the channel 17 and thereby automatically cut off the supply of air. Simultaneously with this movement, any air 5 which may tend to leak from around the pin will be prevented by the packing rings 11-11.

When it is desired to couple the car the knuckles will necessarily be swung into the 10 position shown in Fig. 1 and the air line between the knuckles and the pipe will be automatically opened, as hereinbefore described.

A socket 30 is formed upon each of the 15 coupler heads 5 to receive corresponding lips 31 of the opposed coupler heads, whereby these coupler heads are held against relative vertical movement.

Having thus fully described my invention, 20 what I claim is:—

1. A combined car coupler and air pipe coupling comprising a coupler head, a non-rotatable pivot pin carried by said head and provided with a pipe receiving nipple, said 25 pin having an air channel communicating with the exterior through said nipple and a knuckle journaled on said pin and provided with an air channel having one of its open-

ings at the inner side of the knuckle tongue the other opening of said channel registering with the air channel of the pivot pin in the closed position of the knuckle. 30

2. A combined car coupler and air pipe coupling comprising a coupler head, a non-rotatable pivot pin carried by said head and 35 provided with a pipe receiving nipple, said pin having an air channel communicating with the exterior through said nipple and a knuckle journaled on said pin and provided with an air channel having one of its open- 40 ings at the inner side of the knuckle tongue the other opening of said channel registering with the air channel of the pivot pin in the closed position of the knuckle, said 45 knuckle being provided adjacent its inner face with a dove-tailed seat and a resilient gasket member in said seat which comprises a projecting yielding flange.

In testimony whereof I have hereunto set my hand in presence of two subscribing witnesses. 50

HERMAN WALCH.
